AIRCRAFT HAVING SUSTAINING ROTORS

Joseph S. Pecker, Philadelphia, Pa., assignor to
Autogiro Company of America, Philadelphia,
Pa., a corporation of Delaware

Application September 5, 1931, Serial No. 561,344

23 Claims. (Cl. 244—19)

This invention relates to aircraft having sustaining rotors and is particularly concerned with a craft of the type in which the rotor is composed of a plurality of sustaining blades which are pivoted or articulated to an upright axis structure.

Among the more important objects of the invention are simplification of the rotor blade mounting parts, the arrangement of the mounting structure in general so that a minimum of parasite drag and the like is produced, and the provision of a mounting structure which, in general, is relatively small in overall dimensions and weight.

As a further object, the invention has in view a novel arrangement of means for controlling pivotal blade movements, the arrangement being such that a minimum of space is occupied thereby and the parts being constructed so as to lie closely adjacent the central hub or axis mechanism, this being of importance as it still further reduces the overall dimensions of the rotor head as a whole and thus decreases parasite drag, skin friction, etc.

The general nature of the invention as well as objects and advantages in addition to those noted above will be more apparent from a consideration of the following description making reference to the accompanying drawings, in

which:

Figure 1 is a somewhat diagrammatic side elevational view of a craft of the type here involved, this craft being equipped with a rotor mount constructed in accordance with this invention;

Figure 2 is a vertical sectional view through the rotor mounting and axis structure, this view including a fragmentary showing of the root end of one of the sustaining blades as well as various other elements considered more in detail hereinafter;

Figure 3 is a top view, partly in plan and partly in horizontal section, of the hub structure illustrated in Figure 2;

Figure 4 is a view in horizontal section, similar to Figure 3, of a slightly modified structure; and

Figure 5 illustrates another modification.

The type of craft with which the present invention is concerned, such being illustrated in Figure 1, is provided with forward propelling means including an engine 5 and a propeller 6 mounted at the forward end of the fuselage 7. At the rear end of the fuselage an empennage structure 8 is provided and suitable landing gear

9 may be disposed below the body preferably in the vicinity of the supplementary fixed wings 10.

The rotor system is composed of a plurality of blades 11 which are mounted on the axis 12 mechanism indicated generally at 12, the latter being supported, preferably above a cockpit 13 of the fuselage, as by means of post or leg elements 14 and 15. In order that the blades may be free independently to assume various positions of equilibrium under the influence of inertia, lift and other forces of flight, they are preferably pivoted on two different axes to the central hub mechanism. One of these axes is indicated by the reference numeral 16, this one being extended substantially horizontally, while the other one appears at 17 and, as shown, is extended generally vertically. The showing of the articulations in Figure 1, of course, is diagrammatic, and it is noted that these structures are considered more in detail hereinafter.

Rotor driving means, especially adapted to initiate rotation of the blade system prior to take-off, may also be provided and, in Figure 1, a driving shaft 18 is illustrated as extended obliquely upwardly from the fuselage of the craft just rearwardly of the engine 5 to a point adjacent to the apex structure 19 on which the axis 12 is mounted. Various features of a starter or driving mechanism of the type more or less diagrammatically illustrated in Figure 1 constitute the basis of my copending application, Serial No. 512,383, filed January 30th, 1931.

From inspection of Figures 2 and 3 it will be seen that the apex structure 19, which is supported at the top of the post or leg elements 14—15, is provided with a socket 20 adapted to receive the internal spindle or shaft 21. This spindle 21 is rigidly secured in its socket 20 by means of a flange 21a, which abuts against the upper edge of the socket 20, when the securing nut 21b is tightened in position. The flange 21a may also be recessed at one or more points in order to receive one or more upward projections or lugs 20a which are formed at the upper edge of the socket 20 and which thus serve to positively prevent relative rotation of the internal spindle 21 and the spindle socket.

Ball bearings 22, 23 and 24 are arranged around the spindle 21, at least two of these bearings being vertically spaced from each other by means of a spacer 23a in order effectively to take the radial loads during rotation of the blades. The head structure, of course, also in-

cludes a rotatable hub part 25 which is mounted to rotate on the bearings 22, 23 and 24.

The main rotor bearings 22, 23 and 24 as well as the spacer 23a are also secured to the central spindle 21 by means of a nut device or structure 21c which reacts, through the inner bearing races and the spacer 23a, against the spindle flange 21a. The flange 21a of the spindle 21, therefore, serves not only as an abutment 10 against which the nut 21b may react in securing the rotor, as a whole, to the supporting structure, but also as an abutment for use in positioning the various bearings which are disposed between the two primary and relatively rotatable axis parts.

As in the copending application of Juan de la Cierva, Serial No. 145,655, filed November 1st, 1926, the blades 11 are each provided with two pivoted joints which serve to connect them to 20 the hub 25. In accordance with this invention, however, the substantially vertically extended pivot axis for each blade is disposed between the axis of the hub as a whole and a substantially horizontally extended blade pivot axis. As 25 appears most clearly in Figures 2 and 3, a pair of lugs 26-27, for each blade, is extended outwardly from the hub member 25 at points adjacent to the bearings 23 and 24 and these lugs are vertically apertured to receive the pivot pin 30 28. Bearing bushings 29 may also be interposed between the pin 28 and the lugs 26 and 27.

A joint part 30 is mounted around the pin 28 between the lugs 26 and 27 and is apertured horizontally to receive the pivot pin 31. The 35 connection to the blade is completed by means of apertured fork parts 32-32 which are arranged at the end of the blade root 11a. The forks, of course, are also apertured to receive the pin 31 so that two articulations or pivot 40 joints are provided between the blade itself and the hub structure 25. Bearing bushings 33 may be interposed between the pin 31 and the forks 32-32.

In order to prevent rotation as well as longitudinal displacement of the pin 31, I preferably 45 employ a bolt 31b which is threaded into the joint part 30 and has its inner end extended into a complementary groove formed substantially tangentially of the pin 31. It will also be 50 observed, as indicated at 31c, that the horizontal pin 31 is extended generally tangentially of the pin 28 and fits into a recess formed in the outer surface thereof. This interengagement of the pins 28 and 31 provides for positioning of the 55 former by engagement with the latter, it being apparent that longitudinal displacement as well as rotation of the pin 28 is prevented by such engagement. Thus, only a single removable positioning bolt (31b) is employed in order to 60 position both the horizontal and vertical articulation pins for each blade.

By arranging the blade pivots in the manner above described, the vertical articulation may 65 conveniently be brought in closely adjacent to the hub, as clearly shown in the drawings, so that, in effect, the blade articulations, together with the central hub parts, constitute only one single mass or structure, with the result that, in flight, skin friction and parasite drag are 70 reduced to a minimum.

It is also to be observed that the arrangement shown provides for a compact head structure in view of the fact that the horizontal articulation may also be brought in relatively close to 75 the vertical pivots. As a further advantage of

this construction, it is to be observed that the lugs 26-27 may conveniently be disposed radially outwardly of the ball bearings 23 and 24 so that the strains, thrusts and the like of flight operation are efficiently distributed and 80 transmitted to the central and fixed spindle 21. It is further to be observed that the upper and lower flanges 25a and 25b of the hub member are disposed in the general planes in which the lugs 26 and 27 as well as the bearings 23 and 24 are located. The relative disposition of these flanges, the bearings and the blade attaching lugs is of considerable advantage in providing adequate strength as against all the stresses of flight operation, especially since the flanges serve as reinforcements in the regions where the loads are more or less concentrated. The flanges 25a and 25b also serve additional purposes referred to hereinafter.

In addition to the foregoing, the particular blade joint mechanism lends itself readily to the application of a stop member 34 which is mounted at the outer side of the joint part 30 in position to limit abnormal upward movements of the blades, this part 34 being extended in 100 such manner as to lie between the blade forks 32-32, and contact with the base of the blade root member 11a. The stop 34 may conveniently be attached to the joint part 30 by means of the pin setting bolt 31b and/or an additional 105 bolt or bolts such as indicated at 34a.

In order to control pivotal blade movements about their vertically extended pivots 28, the joint part 30 is preferably provided with abutments 35 arranged to react against rubber blocks 110 36 when the blade swings fore and aft within its general path of rotative travel. The blocks 36, as appears most clearly in Figure 3, are disposed between the abutments 35 and a portion of the hub 25, so that they utilize space 115 closely adjacent to the hub which is well shielded. Thus they do not add to the parasite drag or skin friction of the head as a whole. These blocks 36, according to this form, are secured to and carried by the abutments 35 by means 120 of bracket members 36a, the latter being attached to the abutments themselves as by means of bolts 36b.

For purposes of lubrication, I preferably construct the two pivot pins 28 and 31 with central 125 apertures or bores 28a and 31a which may conveniently serve as a reservoir for oil or grease, preferably the latter. The lubricant may be introduced through suitable fittings such as indicated at 37 and a port 38, disposed at the point 130 where the pins interengage, may be provided so that lubricant may pass between the bores of the two pins. The lubricant may suitably be fed, under the influence of centrifugal force, through the ports 39, these being provided between the interior of each one of the pins and the bearing bushings surrounding them. Certain features of lubrication of this general type are described and claimed in the copending application of Agnew E. Larsen and Joseph S. 140 Pecker, Serial No. 560,314, filed August 31st, 1931.

Above the main rotor hub bearings 22 and 23, I have arranged an extension 40 to which elements 41 are secured, these elements being extended to the blades in order to support them when they are inactive or at rest (see Figs. 1 and 2). The cone or tip 40 may conveniently be attached as by means of bolts to the upper hub flange 25a as clearly seen in Figure 2. 150

The mounting of the blade supporting elements 41 preferably includes two pivot joints 41a and 41b which connect the element 41 proper to a bushing 41c the latter being mounted with freedom for rotation about the upper end of the cone 40. By this means, very great freedom for flexure in movement of the elements 41 as the blades pivot on their individual articulations is provided for without subjecting the upward extension 40 of the rotor head to any material torsional stresses.

The head structure may also conveniently embody a rotor brake. In this instance, the brake includes a downwardly open drum 42 secured to the hub 25 and serving to house internal brake parts 43. The drum 42 is secured to the lower hub flange 25b and is also arranged to support the ring gear 44 which is adapted to cooperate with the pinion diagrammatically indicated at 45 in Figure 2, this pinion being a portion of the rotor driving mechanism. The brake mechanism forms no part of the present invention per se but is described and claimed in my copending application, Serial No. 545,451, filed June 19th, 1931.

According to the foregoing, the present invention provides a rotor head structure, all the parts of which are compactly arranged so that parasite drag and the like are reduced to a minimum. At the same time, the various bearings and blade joints are so constructed as to withstand relatively heavy strains and stresses, with an ample margin of safety, even though the parts themselves are of relatively small size and total weight.

Turning now to the modification of Figure 4 attention is called to the fact that the general arrangement of hub and blade joint parts is quite similar to that of Figures 2 and 3. According to this arrangement, however, the blade joint part 30a is not provided with stops or abutments such as those indicated at 35 in Figure 3. In place of this arrangement I have constructed the blade forks 32a—32a in such manner as to serve as the abutment against which the rubber blocks 46 react. As a further modification, the arrangement of Figure 4 includes only a single rubber block mounted adjacent to the hub between each of the adjacent blade attaching lugs 26a. Each block 46, furthermore, is embraced by a bracket or clip 47, having flanges at top and bottom which, in turn, is secured to the webs 48 extended between the blade attaching lugs as by means of a bolt or pin 49.

In Figure 5 a further modification of blade movement controlling means is illustrated. This structure is also somewhat similar to the showing of Figure 3 but, in this instance, the individual resilient blocks 50 are mounted within sockets 51 formed at one side of the abutments 35a. Each block may be secured in place by means of a bolt 52 threaded into a collar 53 which latter may be moulded into the block itself. By this means, the mounting for the resilient bumpers is considerably simplified, it being noted particularly that no bracket members need be employed in order to position and secure them. As shown, furthermore, the bumpers 50, when the blade is in neutral position, are somewhat spaced from the hub member 25, although it should be understood that, if desired, the arrangement may be modified so that the bumpers 50, similarly to those indicated at 36

in Figure 3, will remain under compression at all times.

At this point it should be observed that the general blade articulation arrangement of all forms of hub structure herein illustrated provides for the disposition of blade movement control means closely adjacent to the hub itself so that a neat and compact structure results. The particular pivot arrangement, furthermore, is adaptable to a number of different types of blade movement controlling means as will readily be apparent from inspection of Figures 3, 4 and 5. In Figure 3 the bumpers 36 are illustrated as being under compression at all times, while in Figures 4 and 5, the arrangements are such that the rubber blocks come into operation only after a given or predetermined angular displacement of the blades about their vertical articulations. Furthermore, in Figures 3 and 5, a pair of cushions is employed for each blade, while in Figure 4, each one of the blocks employed cooperates with two adjacent blades in order to control movements about their vertical articulations. Finally, from comparison of Figures 3 and 5, it will be seen that the abutments or stops associated with the joint part 30, as well as the associated rubber blocks, may be arranged either to remain under compression at all times or to come into operation only after a given angular displacement of the blades.

Thus, where various characteristics of the craft as a whole indicate that one or the other of the control mechanisms should be employed, this may readily be done, since the general arrangement of the parts is "universal" in character, that is, any one of a number of different blade movement control devices may conveniently be applied between the hub structure and the blade fork itself or an abutment moving therewith.

Finally, it should be observed that the novel arrangement of blade pivots or articulations is such that the horizontal as well as the vertical joints may conveniently be brought in very close to the rotor head. This is of substantial importance since decreasing the overall general diameter of the hub materially reduces drag and the like so that the efficiency of the craft as a whole is considerably enhanced.

The vertical articulation, as will be apparent from inspection of the various figures of the drawings, is extended closely adjacent to the hub with the result that the blade attaching lugs have great strength even though they be made relatively light in construction. This arrangement is also desirable since the blade attaching lugs are disposed closely adjacent to the main rotor hub bearings, the result of this being substantially direct transmission of thrust to the central and fixed axis part. The strength of this general structure is further increased by the disposition of flanges or ribs adjacent the upper and lower edges of the hub part proper, these ribs serving, in addition, as a means of attachment of the rotor tip or cone 40 and the rotor brake drum 42.

It is further observed that the two pivot pins for each blade are fixed in a single joint part of very small overall dimensions, it being noted that this block is provided with a pair of bores extended perpendicularly to each other so that the lugs 26 and 27 of the hub 25 as well as the blade forks 32—32 embrace the joint block and, indeed, even overlap somewhat with respect to each other. In this way, the joint parts are

constructed to occupy a minimum of space. The very simplicity and small dimensions of the blade joints, particularly the block part 30, in addition to reducing drag and total weight, also increases the strength of the structure as a whole.

The interengagement of the horizontal and vertical pivot pins for each blade is also of advantage as it permits the use of a very simple means for positioning and securing the pins in their operative positions. This construction is also advantageous in permitting the use of a lubricant duct extended between the reservoirs provided in the pins, so that, in effect, the pin cavities are joined in one relatively large reservoir and, when suitably packed with grease, thorough lubrication of both pins will always be provided.

A further advantage of the structure above described resides in the fact that the hub member proper is of such configuration that its manufacture is greatly simplified as compared with hub structures heretofore employed. In this connection, it is noted that substantially no milling work need be performed for the reason that the various lugs, flanges, etc., may readily be turned in a very simple manner.

What I claim is:—

1. In an aircraft having a sustaining rotor, relatively movable axis members with vertically spaced bearings therebetween, a sustaining blade articulated to an axis part on a substantially upright axis, and vertically spaced articulation parts disposed adjacent said vertically spaced bearings to provide an articulation bearing adjacent to each.

2. In an aircraft having a sustaining rotor, relatively movable axis parts with vertically spaced bearings therebetween, a sustaining blade, and means for securing said blade to an axis part, said means including flexible joint parts disposed adjacent said vertically spaced bearings to provide an axis for blade movements extended substantially parallel to the axis of the said axis parts.

3. An aircraft having a sustaining rotor, and means for mounting the blades of the rotor including a common axis structure and joint means providing for swinging movements of the blades with respect to said structure, said joint means including parts providing one pivot axis extended generally vertically closely adjacent the said structure and another pivot axis extended generally horizontally at a point spaced radially outwardly from the other joint axis, together with an abutment associated with joint parts and means for controlling blade joint movements interposed between said abutment and a portion of said axis structure.

4. In an aircraft having a sustaining rotor, an axis structure, a sustaining blade pivoted to said structure on a substantially vertically extended axis, and means for controlling pivotal blade movements, said means including an abutment movable with a blade pivot part, and a resilient device interposed between said abutment and a portion of the said structure.

5. In an aircraft having a sustaining rotor, an axis structure, a sustaining blade, and means for pivoting said blade to said axis structure, said means including a substantially vertically extended pivot and a cooperating pivot joint part movable with the blade, together with a mechanism for controlling pivotal blade movements, said mechanism including an abutment

movable with the said cooperating part and a resilient device interposed between said abutment and a portion of the said structure.

6. In an aircraft having a sustaining rotor, an axis structure, a sustaining blade, and means for pivoting said blade to said axis structure, said means including a substantially vertically extended pivot, a substantially horizontally extended pivot and a joint part cooperating with said pivots and movable with the blade about the substantially vertical pivot axis, together with a mechanism for controlling pivotal blade movements, said mechanism including an abutment movable with the said joint part and a resilient device interposed between said abutment and a portion of the said structure.

7. In an aircraft having a sustaining rotor mounted for rotation about an upwardly extended axis, an axis structure, a sustaining blade pivoted thereto, and means for controlling pivotal blade movements arranged to react between a part movable with the blade and said axis structure, there being a plurality of sustaining blades pivoted to the structure, together with a plurality of controlling means disposed about the axis structure between the points of pivotal attachment of the blades, and each arranged for cooperation with a plurality of blades.

8. In an aircraft having a sustaining rotor, a mounting structure for the rotor including a hub structure having apertured lugs for pivotal attachment of sustaining blades thereto, the lugs being spaced from each other about the axis, and means for controlling pivotal blade movements mounted on the hub structure between adjacent lugs.

9. An aircraft having a sustaining bladed rotor and a blade mounting structure, a fork at the inner end of a blade, pivot means joining the fork to said structure, the pivot means including pivot joint parts providing for movement of the blade on a substantially vertically extended axis, and means for controlling blade pivot movements about said vertical axis, said means being arranged to react between said structure and a portion of said fork.

10. In an aircraft having a sustaining rotor, an axis mechanism, a sustaining blade pivotally attached to the axis mechanism, and means for controlling pivotal blade movements, said means including a resilient device mounted on a part movable with the blade about its pivot axis and arranged to react against a part not so movable, the movable part being socketed to receive the device, together with means for securing the said device in the socketed part.

11. For an aircraft of the pivoted and rotatively mounted blade type, a mechanism for controlling pivotal blade movements, said mechanism including a rubber bumper having means of attachment to a cooperating part, and said means being embedded in the rubber.

12. For an aircraft of the pivoted and rotatively mounted blade type, a mechanism for controlling pivotal blade movements, said mechanism including a rubber bumper having means of attachment to a cooperating part, and said means including an internally threaded collar embedded in the rubber.

13. A hub structure for an aircraft sustaining rotor, said hub structure having strengthening flanges at top and bottom, a plurality of blades connected with the hub, a rotor brake part attached to the lower flange, and means for

- supporting the blades when they are inactive or at rest, said means being secured to said upper flange. means being disposed between a pivot part and a portion of the axis structure.
14. In an aircraft having a sustaining rotor, an axis structure, a sustaining blade pivoted thereto, and pivot joint parts including a pair of pivot pins and a block apertured to receive said pins, together with means for fixing both of said pins as against rotation in said block. 21. In an aircraft, a sustaining rotor mechanism including a hub having a generally upright axis, a plurality of blades arranged around the hub for autorotational actuation under the influence of relative air-flow in flight, and pivot devices for securing each blade to the hub, said devices including a generally horizontal pivot providing for upward and downward blade swinging movements, an additional pivot the axis of which is extended at an angle to the longitudinal axis of the blade and lies substantially in the plane containing the longitudinal axis of the blade and the upright axis of the rotor, said additional pivot further being positioned intermediate the generally horizontal pivot and the said rotor axis, and a lug on the hub for attachment of said additional pivot thereto, the lug being provided with an aperture to cooperate with the pivot and being extended from the main body of the hub a distance not greater than a fraction of the diameter of the hub, whereby to position said additional pivot in close proximity to the hub. 80
15. In an aircraft having a sustaining rotor, an axis structure, a sustaining blade pivoted thereto, and pivot joint parts including a pair of pivot pins, one extended generally vertically and the other extended generally horizontally, and a block apertured to receive said pins, the said pins being arranged for cooperative interengagement whereby one is positioned by the other, together with means for positioning the said other pin. 85
16. In an aircraft having a sustaining rotor, a hub structure for the rotor, a sustaining blade flexibly jointed to the hub structure, and flexible joint parts including a pair of pivot pins arranged substantially tangentially to each other. 90
17. In an aircraft having a sustaining rotor, a hub structure for the rotor, a sustaining blade flexibly joined to the hub structure, and flexible joint parts including a pair of pivot pins arranged substantially tangentially to each other and having complementary interengaging parts formed to provide for positioning of one pin by engagement thereof with the other. 95
18. In a multi-bladed aircraft sustaining rotor, a hub structure to which the blades are pivotally connected, a structure extended above the hub and arranged for rotation therewith, and means for supporting the blades when they are inactive or rotating below normal flight speeds, said means including support elements extended from the blades to the structure last mentioned and being joined to a device mounted for movement about the axis of the rotor, together with pivot joints connecting said elements 100
- 45 with said device. 110
19. In a multi-bladed aircraft sustaining rotor, a hub structure to which the blades are pivotally connected on substantially horizontally extended and substantially vertically extended axes, a structure extended above the hub and arranged for rotation therewith, and means for supporting the blades when they are inactive or rotating below normal flight speeds, said means including support elements extended from the blades to the structure last mentioned and being joined to a device mounted for movement about the axis of the rotor, together with substantially horizontal and substantially vertical pivot joints connecting said elements with said device. 115
- 50 20. In an aircraft having a sustaining rotor, rotor blades or wings, an axis structure for said blades or wings, a pivot device having a generally vertical pivot part joining a sustaining blade to the axis structure with freedom for force compensating movements about a substantially vertically extended axis, and means for controlling force compensating blade movements, said 120
- 55 21. In an air craft, a sustaining rotor mechanism including a hub structure incorporating relatively rotatable elements, bearing means between said elements, a plurality of blades arranged around the hub for autorotational actuation under the influence of relative air flow in flight, and pivot devices for securing each blade to a hub element, said devices including a generally horizontal pivot providing for upward and downward blade swinging movements, an additional pivot the axis of which is extended at an angle to the longitudinal axis of the blade and lies substantially in the plane containing the longitudinal axis of the blade and the upright axis of the rotor, said additional pivot being located between the pivot first mentioned and the axis of the rotor, and lug means secured to the hub element and cooperating with said additional pivot for mounting the additional pivot on the hub element, said lug means being disposed substantially radially outwardly of the bearing means and substantially in the plane thereof, whereby centrifugal and other forces incident to rotation are transmitted substantially directly from the lug means through the hub element which is rotatable with the rotor and through the bearing means to the other hub element. 125
- 60 22. In an aircraft having a sustaining rotor, an axis structure, apertured lug means on the axis structure, a sustaining blade having apertured lug means, and pivot joint parts for pivotally connecting said two lug means including a pair of pivot pins and a block apertured to receive said pins, one pin cooperating with the lug means on the axis structure and the other with the lug means on the blade, together with means for fixing both of said pins as against rotation in said block to provide for pin movement within the apertures of the lug means. 130
- 65 23. In an aircraft having a sustaining rotor, rotor blades or wings, an axis structure for said blades or wings, a pivot device having a generally vertical pivot part joining a sustaining blade to the axis structure with freedom for force compensating movements about a substantially vertically extended axis, and means for controlling force compensating blade movements, said 135
- 70 140

JOSEPH S. PECKER.
